UNITED STATES PATENT OFFICE.

GEORGE W. WRIGHT, OF LOS ANGELES, CALIFORNIA.

DEEP-WELL PUMP.

Application filed July 20, 1924. Serial No. 729,089.

This invention relates generally to pumps, and is more particularly concerned with so-called "deep well pumps" of the type used in oil and artesian wells. It is an improvement over the pumps described in United States Letters Patent No. 1,419,436, issued to me June 13, 1922.

Due to the abrasive action of the sand and grit usually present in the fluid being pumped, great difficulty is experienced in keeping pump plungers properly packed, and once the packing breaks down or ceases to function properly, pump efficiency drops rapidly.

Generally, therefore, it is among the objects of my invention to provide a pump having means for keeping the plunger properly packed irrespective of wear, the packing being kept constantly under approximately uniform pressure by the action of compression springs. There is a supply of reserve packing which is spring-pressed into operative position as the active packing wears away, so the plunger only has to be withdrawn for repacking when the reserve supply is exhausted.

By reason of these provisions, the necessity for withdrawing the pump for repacking arises infrequently and the pump is in condition to render efficient performance during the entire period between successive withdrawals. This is in contra-distinction to usual pumps which have to be frequently withdrawn for repacking and which function with full efficiency only when newly packed.

I also provide for the efficient and constant lubrication of the packing and actuating springs. This lubrication has the usual beneficial effect on the springs and maintains the packing in the soft, pliable condition necessary to enable it to perform with high efficiency.

In the structure here disclosed, the packing is carried on and movable with the plunger rather than being held by the pump barrel, as is true in the aforementioned patent. Therefore, it is desirable when occasion arises for repacking, that the barrel be withdrawn from or inserted in the well casing with the plunger in place within the barrel, rather than that the plunger be withdrawn or inserted by forcing it through the tubing by means of the sucker rods. The same is

true when initially installing the pumps; that is, it is desirable that the plunger be in operative position within the barrel when the latter is lowered into place, rather than first setting the tubing and barrel and then lowering the plunger through the tubing by means of the sucker rods.

Therefore, I have devised a novel coupling whereby the sucker rods may be attached to and disengaged from the plunger when the latter is in position within the barrel at the bottom of the hole.

Other features of novelty and objects of the invention will be set forth in the following detailed specification, reference being had to the accompanying drawings, in which—

Fig. 1 is a view of a pump embodying the present invention, showing it installed in a typical well casing;

Fig. 2 is an enlarged detailed sectional view of the upper portion of the pump;

Fig. 3 is an enlarged, contracted sectional view of the central portion of the pump, being a continuation of Fig. 2 and repeating, at its upper end, a small portion of the lowermost structure shown in Fig. 3;

Fig. 4 is an enlarged, contracted sectional view of the lower portion of the pump, being a continuation of Fig. 3;

Fig. 5 is a broken away elevation, partly in section, of Fig. 2 as viewed from the position of arrow 5; and

Fig. 6 is a perspective view of a latch making up part of my coupling mechanism.

First, referring to Fig. 1, numeral 10 designates a well casing in which is arranged tubing 11. Coupled at 12 to the lowermost length of the tubing, is pump 13, the plunger 14 of which is adapted to be reciprocated by sucker rods 15 in the usual manner. At the lower end of pump barrel 16 is a usual foot valve 17, while the plunger has an inlet valve 18 at its lower end and an outlet port 19 (Fig. 2) near its upper end.

Without going further into the structure of the pump, it will be readily understood that an upstroke of plunger 14, as accomplished by lifting rods 15, opens foot valve 17, drawing a charge of fluid from casing 10 into the pump barrel between valve 17 and the lower end of plunger 14; while a down stroke of the plunger opens valve 18 to pass the barrel-contained fluid into plunger 14.

er bore 14^a to displace the fluid previously admitted to said bore; the displaced fluid passing through port 19 into the upper chamber 13^a of the pump and thence to tubing 11.

The structure herein so far described is more or less typical of deep well pumps, but I will now proceed to a description of the means employed for packing the plunger in 10 a manner to prevent the flow or leakage of fluid between the outer peripheral face of the plunger and the inner peripheral face of the barrel, whereby the fluid flow is confined to passage through plunger bore 14^a. In 15 this packing means lies part of my invention.

While, in its broader aspects, my invention contemplates the use of a plunger made up of a single length of tubing provided with the usual valves and my novel packing means, I have illustrated a preferred structure wherein the plunger includes a plurality of tubular lengths or sections coupled in end to end relation. The coupling means have additional function in connection with the packing means, as will be apparent presently.

While I have illustrated and will describe the plunger as including a certain number of tubular sections and as having three areas 30 of packing throughout its aggregate length, it will be understood the invention is not limited to any particular number of sections or packing areas.

Plunger 14 includes four sections of tubing 20, 21, 22 and 23; the uppermost section 20 being provided with outlet port 19 and carrying one element of a coupling 24 whereby connection is made between the plunger and sucker rod. For the present we will 40 disregard the structural features of said coupling and merely specify that, preferably, it is in the nature of a clutch rather than the usual screw thread connection.

Sections 20, 21 are coupled by packing-seat bushing 25; sections 21 and 22 are coupled by spring-seat collar 26; sections 22, 23 are coupled by the combination packing-seat and spring-seat bushing 27; and packing-seat bushing 28 is carried at the lower 50 end of section 23 and serves to support valve 18.

Now referring particularly to Fig. 3, it will be observed that the outer peripheral face 29 of the upper portion 30 of bushing 25 fits the inner peripheral face of barrel 16 with sufficient tightness to prevent sand or other foreign matter from passing from above the plunger to the packed area of the plunger, below. However, the fit between 60 the barrel and bushing is sufficiently easy to allow free reciprocation of the plunger within the barrel. Thus, bushing 25 serves both as a guide bearing between the plunger and barrel, and prevents the passage of foreign matter to the packing. The upper end 29

of bushing 25 acts as a scraper or wiper for cleaning the barrel during upstrokes of the plunger.

The lower end 31 of bushing 25 tapers inwardly to define a chamber 32 for the reception of active packing 33 which is of a relatively soft, pliable and compressible nature, it being of any material having the characteristics necessary to fulfill the requirements.

The outer peripheral face 34 of collar 26 fits the barrel with working clearance and its ends 35, 36 are of slightly reduced diameter to take the ends of sleeve or tubular skirts 37, 38 respectively; these sleeves being secured to the collar in any suitable manner, for instance by screws 39. Of course, it lies within the scope of my broader claims to make sleeve 37 integral with either collar 26 or section 21. Considering only sleeve 37, 85 it will be noted that this sleeve is annularly spaced from section 21 and extends upwardly to a point approximately opposite the lower end of bushing 25. The outer face of the sleeve may be of easy fit with barrel 16 or may have considerable clearance with respect thereto.

Section 21 and sleeve 37 define an annular space 40 which provides a reserve packing chamber 41 for reserve packing 42, and a 95 spring chamber 43. A compression spring 44 is interposed between the two sets 45, 46 of packing rings, these rings preferably being relatively hard and stiff (leather, for instance). Rings 45 rest on the upper ends 100 or shoulders 47 of collar 26, while rings 46 are immediately beneath reserve packing 42. Preferably, when the plunger and barrel are assembled, oil is placed within chamber 40 in order to provide constant lubrication 105 for the plunger, packing and spring, with obvious advantage.

As the active packing 33 wears away during pump operation, spring 44 feeds the reserve packing into chamber 32 to replace 110 said worn away packing; it being observed that the lowermost end of bushing 25 is curved inwardly or cut away at 47^b to provide a relatively large throat between chambers 32 and 41, and that there are no pockets 115 or corners in which the packing may become lodged or caught to prevent the proper feed of reserve packing.

Spring 44 acts, through reserve packing 42, to keep active packing 33 under constant 120 and substantially uniform pressure, and the shape of chamber 32 as defined by bushing 25, and the proportionate size of throat 47^a is such that the active packing is held against barrel 16 with substantially uniform pressure 125 throughout the extent of said packing.

Sleeve 37 serves both as the outer wall of chamber 40 to hold the body of reserve packing from contact with the plunger, and to establish the effective length of active pack- 130

ing chamber 32. It is found in actual practice that while it is desirable that the area of contact between barrel and packing be as large as possible, there is a limit to the 5 permissible extent of said area and if this limit be exceeded the packing will seize the barrel and prevent proper gravitation of the plunger. The limit is variable for it depends on the condition of the individual 10 installation.

Therefore, sleeve 37 may be cut to such length that, in a given installation, a proper area of active packing is exposed to the barrel. If desired, the sleeves may be manufactured in different lengths and, by making the sleeve connection interchangeable, a sleeve of proper length for a given installation may be chosen and exchanged for the sleeve originally affixed to collar 26.

20 It will be observed that the upper portion 48 of bushing 27 is tapered similarly to portion 31 of bushing 25, and that spring 49, interposed between relatively hard packing rings 50 and 51 (rings 50 contacting with the lower ends of collar 26) and housed between section 22 and skirt 38, serves to force reserve packing 52 from chamber 53 into chamber 54 for replacing active packing 55 as the latter wears away.

30 The lower end 56 of packing-seat bushing 27 is formed similarly to the ends of spring-seat collar 26, and supports skirt 57 which defines spring chamber 58 and reserve packing chamber 59. Relatively hard packing rings 60 are held against end 56 by spring 61, the opposite end of said spring bearing on packing rings 62 in a manner to feed reserve packing 63 into chamber 64 (the latter chamber being defined by the upper, 40 tapered end 65 of packing-seat bushing 28) to replace active packing 66 as the latter wears away.

Bushings 27 and 28 have portions 67 which bear against barrel 16 in a manner similar 45 to that described in connection with portion 30 of bushing 25. Portion 67 of bushing 28 serves also to prevent the passage of sand and other foreign matter to packing 66 from below the plunger.

50 It is desirable that plunger 14 be installed within barrel 16 before the latter is lowered through casing 10, and also, when occasion arises for replenishing the supply of packing, that the barrel be withdrawn with the 55 plunger in place therein. Therefore, I have devised a novel coupling whereby the plunger and sucker rods may be connected and disconnected when the plunger is in position at the bottom of the well. This coupling, 60 which I will now proceed to describe, is in the nature of a clutch, and is operable by relative longitudinal movement of the plunger and sucker rods, rather than by relative rotation therebetween, as is true in the 65 ordinary screw-thread type of connection.

Referring particularly to Figs. 2, 5 and 6, I have shown body member 68 of coupling 24 as being integral with plunger section 20, though, of course, it lies within the scope of my invention to detachably connect 70 said member and section. Member 68 is tubular, the bore 69 thereof being adapted to receive the headed end 70 of sucker rod 15. Head 70 is preferably conical, and shoulder 71 is formed between the base of 75 the head and neck 72, which latter is preferably of smaller diameter than rod 15. The lower end of head 70 is adapted to bear against member 20 and 73 so that down movement of rod 15 forces a like movement 80 of plunger 14. Having lost motion pivotal connection with pins 74, are latches 75 (there being any desired number of such latches arranged about tube 68) said pins being supported by tube 68, and said latches being 85 adapted to swing vertically on said pins through slots 76 which open to bore 69.

A sleeve 77 is longitudinally slidable on tube 68 (relative rotation between the sleeve and tube being limited by the pin and 90 slot connection 78) and a spring 79, interposed between shoulder 80 on the tube 68 and shoulder 81 on sleeve 77, tends to keep said sleeve at its upper limit of movement over tube 68, said limit being established by 95 the pin and slot connection 78. Sleeve 77 is slotted at 82 to allow the swing of latch 75 therethrough, and a sleeve-carried spring 83 is adapted to yieldably urge or bias the latch towards rod 15 in such a manner that latch shoulder 84 engages rod shoulder 71, whereby upward movement of rod 15 causes like movement of plunger 14.

With sleeve 77 at its upper limit of movement over tube 68, there is no operative engagement between said sleeve and latch 75 except for the co-action of spring 83 with said latch, and therefore, when the sucker rods are stroked, plunger 14 is operated in the usual manner.

110 However, when occasion arises for withdrawing the sucker rods, said rods are lifted higher than the normal stroke limit until the upper end of sleeve 77 engages shoulder 85 which projects inwardly from barrel 16. 115 This shoulder may be conveniently provided by the lower end of coupling 12, as shown in Fig. 2. It will be observed that the lower end of sleeve 77 is tapered at 86 and that latch 75 has ears or lugs 87 extending beyond each side of slot 82, the under sides of said lugs being tapered complementarily to end 86. Therefore, when the upward movement of sleeve 77 is checked by engagement of shoulder 85 and the sleeve top, continued 120 upward movement of rod 15 carries latch 75 (and plunger 14) upwardly against the action of spring 79, drawing lugs 87 over sleeve taper 86 and thus swinging latch 75 125 in a clockwise direction, as viewed in Fig. 2, 130

against the action of spring 83. Thus, latch shoulder 84 is disengaged from rod shoulder 71 and the rod, being thus freed from the plunger, may be withdrawn from the well without withdrawing the plunger from the barrel.

Assuming that the plunger has subsequently dropped sufficiently to allow spring 79 to slide sleeve 73 along tube 68 and thus free taper 86 from lugs 87, upon re-inserting rods 15 within tubing 11, head 70 engages and swings latch 75 outwardly, and when the head is subsequently seated at the bottom of bore 69, spring 83 acts to return the latch into operative engagement with the rod.

It will be understood that various changes in design, arrangement and structure, may be made without departing from the spirit and scope of my claims, and therefore, I do not wish to be limited to the illustrated and described embodiment of my invention except for such limitations as a fair interpretation of the appended claims may import.

Having described a preferred form of my invention, I claim:

1. In a pump of the character described embodying a barrel and a tubular plunger therein, the plunger being annularly spaced from the barrel, packing means between the plunger and barrel, said means including a bushing secured to the plunger and having a portion adapted to peripherally engage the barrel, said bushing having an annular shoulder adapted to define one end of a chamber annularly defined by the plunger and barrel, a body of relatively soft packing within the chamber, a spring within the chamber and movable with the plunger, and relatively hard packing between the soft packing and the spring; said spring being adapted to move the hard packing towards said annular shoulder and thereby place the soft packing under compression.
2. In a pump of the character described embodying a barrel and a tubular plunger therein, the plunger being annularly spaced from the barrel, packing means between the plunger and barrel, said means including a bushing secured to the plunger and having a portion adapted to peripherally engage the barrel, said bushing having an annular shoulder adapted to define one end of a chamber annularly defined by the plunger and barrel, active packing within the

barrel, a collar on the plunger and longitudinally spaced from said bushing, a sleeve extending from the collar towards said annular shoulder, said sleeve being annularly spaced from the plunger, reserve packing within a chamber annularly defined by the sleeve and plunger, said chambers being in communication, a spring on the plunger and seated at one end on said collar, the other end of the spring extending towards said reserve packing, and a ring of hard packing interposed between the reserve packing and said other end of the spring, all in a manner whereby the spring is adapted to feed the reserve packing into the first named chamber to replace active packing worn away by the plunger.

3. In a pump of the character described embodying a barrel and a tubular plunger therein made up of tubular sections arranged end to end, the plunger being annularly spaced from the barrel, packing means between the plunger and barrel, said means including a bushing secured to the plunger and having a portion adapted to peripherally engage the barrel, said bushing having an annular shoulder adapted to define one end of a chamber annularly defined by the plunger and barrel, active packing within the chamber, a collar on the plunger and longitudinally spaced from said bushing, said collar being screw-threadedly connected with two of said tubular sections at their meeting ends and thereby securing said tubular sections together, a sleeve extending from the collar towards said annular shoulder, said sleeve being annularly spaced from the plunger, reserve packing within a chamber annularly defined by the sleeve and plunger, said chambers being in communication, a spring on the plunger and seated at one end on said collar, the other end of the spring extending towards said reserve packing, and a ring of hard packing interposed between the reserve packing and said other end of the spring, all in a manner whereby the spring is adapted to feed the reserve packing into the first named chamber to replace active packing worn away by the plunger.

In witness that I claim the foregoing I have hereunto subscribed my name this 22d day of July 1924.

GEORGE W. WRIGHT.
